[57] CLAIM

The ornamental design for a small animal habitat, as shown.

DESCRIPTION

FIG. 1 is an isometric view taken from the top, front right side of a small animal habitat showing my new design;

FIG. 2 is an isometric view taken from the top, rear and left side thereof;

FIG. 3 is a top plan view thereof;

FIG. 4 is a bottom plan view thereof; and

FIG. 5 is a right side elevational view thereof.
